UNITED STATES PATENT OFFICE

HENRY J. WISER, OF OTTAWA, ONTARIO, CANADA, ASSIGNOR TO INTERNATIONAL FIBREBOARD, LIMITED, OF GATINEAU, QUEBEC, CANADA

EXTRACTOR IN PRESSES

Application filed June 2, 1930. Serial No. 459,600.

This invention relates to apparatus for extracting the products of presses and is more especially applicable to presses for manufacturing wall boards from wood pulp.

5 The sheet of compressed pulp produced by such a press is not self-supporting until it has been dried and there is some difficulty in removing the sheets of moist pulp from the press without damaging them. The object of 10 the invention is to provide an improved extracting apparatus which is free from the difficulty mentioned above.

The invention consists in the arrangement, construction and combination of parts hereinafter described and more particularly pointed out in the appended claims.

15 Referring now to the accompanying drawings, which illustrate, by way of example, one convenient embodiment of the invention,

20 Figures 1 to 4 inclusive are diagrammatic side elevations indicating successive positions of the invention during operation,

Figure 5 is a side elevation of the invention on a larger scale, and

25 Figure 6 is a diagrammatic end elevation, partially in section, of a press embodying the present invention.

The invention is applicable to any press for the manufacture of boards from wood or 30 like pulp of the kind in which the pulp is pressed between two dies or plattens. The type of press to which the invention is shown applied in the drawings comprises a stationary upper die 1, a vertically movable lower

35 die 2 and a vertically movable sleeve or deckle 3 which slidably engages the vertical walls of the upper die 1. A pulp inlet 4 is provided on the sleeve 3. The dies 1 and 2 are hollow and their adjacent walls are perforated.

40 Pipes as indicated at 5 are provided for connecting the interior spaces of the dies 1 and 2 to a source of sub-atmospheric pressure. An endless chain or the like 6, carried by wheels 7¹, 7², 7³, 7⁴ is provided on each side of the 45 press and transverse members 8 connect the two chains along a limited portion of their length.

Figure 1 illustrates in diagram the initial 50 position of the parts. In this position the space between the dies 1 and 2 is closed by the

sleeve 3, and into this space the requisite quantity of pulp is fed through the inlet 4. The lower die 2 is then raised, for example, by a hydraulic plunger 9, into the position shown in Figure 2. The sleeve 3 is carried up with the die 2 and during this operation the pressure inside the dies is reduced to cause moisture to be withdrawn from the pulp. Atmospheric pressure is then restored in the movable die 2 and the latter is lowered to its initial position. The reduced pressure is maintained in the top die 1 to prevent the compressed pulp 10 from falling with the die 2.

The extractor, which constitutes the present 65 invention, is then operated to move the chains 6 in the direction of the arrows to bring the transverse supporting members 8 into position beneath the pulp 10, as shown in Figure 3. The movement of the extractor is then 70 arrested, and superatmospheric pressure is created in the interior of die 1 to blow the sheet of pulp 10 from the die on to the supporting section 8 of the extractor. Thereafter the extractor is again moved in the 75 direction of the arrows, and after passing the wheels 7³, the supporting members move in a downward direction, but the pulp sheet 10 has sufficient rigidity to retain its horizontal 80 position and pass straight on to a suitable conveyor 11 (Figure 4), which carries it on to a dryer, not shown. Means, such as an inclined plane 12, may be provided between the extractor and the adjacent end of the conveyor 11 to ensure that the pulp will not 85 be carried down with the extractor. As soon as the sheet of pulp 10 has been extracted, the sleeve 3 is moved down under the control, for instance, of a hydraulically operated plunger 9^a and the cycle of operations is 90 repeated.

Referring to Figure 5, which shows a fragmentary side elevation of one convenient form of the invention, it will be seen that the chains 6 comprise uniformly spaced rollers 95 6^a connected by links 6^b.

The transverse supporting members 8 are secured at their ends to brackets 8^a which in turn are secured to laterally projecting flanges on the links 6^c of the chains 6. 100

A convenient number of the transverse angle members 8 may be provided at their ends with brackets 13 in which rollers 14 are mounted. For example, every third or 5 fourth member 8 may be provided with rollers 14 and the adjacent members 8 are recessed at 15 to accommodate the rollers.

The elements forming the extractor may be applied to the press in any convenient 10 manner. For example, the chain wheels 7² and 7³ may be mounted rotatably on shafts 16 carried by brackets 17 which are secured to horizontal beams 18. The beams 18 are carried by brackets 19 (Figure 6) supported 15 on standards 20 which also support other parts of the press. Secured on top of the beams 18 are channel members 21 in which the rollers 6^a of the chains 6 run.

The wheels 7¹ and 7⁴ are mounted on shafts 20 22 supported in bearings 23 which are mounted, for example, on girders 24 forming part of the foundation of the press. The bearings 23 may be arranged to slide longitudinally 25 of the girders 24 so that the tautness of the chains 6 may be adjusted when necessary, bolts and nuts 25 or equivalent means being provided to hold the bearings 23 in adjusted position. Certain of the chain wheels are connected to a driving shaft. For example, 30 the wheels 7⁴ may be keyed as at 26 to their shaft and any suitable means may be furnished to drive this shaft.

A shoulder or ledge 27 is preferably provided in the foundation or base of the press 35 at each side thereof parallel to and vertically beneath the respective channels 21. The rollers 14 on the transverse supporting section 8 of the extractor roll on the surfaces 27 while the supporting section is travelling from the 40 wheels 7⁴ to the wheels 7¹. The weight of the section 8 is thereby prevented from causing sagging of the lower lap of the chains 6.

The construction and operation of the extractor mechanism only have been described 45 in detail, as the remaining parts of the press are merely incidental to the present invention.

It will be understood that the foregoing 50 description and accompanying drawings are given by way of illustration only and that many modifications may be made without departing from the invention as defined in the following claims.

What I claim is:

- 55 1. In combination with a press having upper and lower pulp-pressing dies, an extractor comprising a pair of endless flexible members arranged one on each of the opposite sides of said dies, and a plurality of transverse members connecting said flexible members and collectively forming a flexible pulp-receiving section extending along a portion of the length of said flexible members.
- 60 2. In combination with a press having upper and lower dies, an extractor comprising

endless flexible conveyor means arranged in vertical planes adjacent opposite sides of the lower die, wheels for supporting and driving said conveyor means, a plurality of rigid transverse members connected adjacent their 70 ends to said conveyor means and forming a flexible pulp-receiving section extending throughout a portion of the length of said conveyor means, and means for supporting said pulp-receiving section in a horizontal 75 position between said dies when the latter are separated.

3. In combination with a press having upper and lower dies, an extractor comprising 80 a pair of endless chains arranged in vertical planes one on each of opposite sides of said dies, chain wheels for guiding and driving said chains and arranged to support the upper sections of both chains in the same 85 horizontal plane, a series of brackets connected to said chains along a portion of their length, and a series of rigid transverse members connected at their opposite ends to said brackets.

4. Apparatus as claimed in claim 3, wherein 90 said chains are of the type comprising spaced rollers connected by pairs of links, and wherein the links of a portion of said chains are provided with flanges to which said brackets are secured.

5. Apparatus as claimed in claim 3, wherein 95 four chain wheels are provided on each side of the press and wherein the upper wheels are mounted in brackets, a horizontal beam being provided to carry said brackets, 100 and a chain supporting channel being carried by said beam.

6. Apparatus as claimed in claim 3, wherein 105 in rollers are mounted on certain of said transverse members, horizontal surfaces being provided adjacent the bottom of the press and arranged to be engaged by said rollers.

7. In a press having upper and lower pulp-pressing dies, means for separating the dies 110 and means for retaining a sheet of compressed pulp on the lower surface of the upper die after the dies have been separated, the provision of an extractor comprising a flexible pulp supporting section and endless conveyor means to hold said supporting section normally removed from said dies and to carry said section into a horizontal position between said dies to receive a sheet of pulp 115 when the dies have been separated.

In testimony whereof I have affixed my signature.

HENRY J. WISER.
